(57) **CLAIM**

We claim the ornamental design for the container for fluid dispensing system, as shown and described herein.

DESCRIPTION

FIG. 1 is a perspective view of the container for fluid dispensing system according to a preferred embodiment of the invention.

FIG. 2 is a top view of the container for fluid dispensing system of FIG. 1.

FIG. 3 is a front elevation view of the container for fluid dispensing system of FIG. 1.

FIG. 4 is a rear elevation view of the container for fluid dispensing system of FIG. 1.

FIG. 5 is a right side elevation view of the container for fluid dispensing system of FIG. 1; and,

FIG. 6 is a left side elevation view of the container for fluid dispensing system of FIG. 1.

The dash-dot-dot line showing on the drawing disclosure is for illustrative purposes only and forms no part of the claimed design.
